PORTABLE CLOTHES DRYER

Mildred S. Bengtson, 149 Alegra Lane,
Walnut Creek, Calif.

Filed Apr. 22, 1960, Ser. No. 60,288

Term of patent 14 years

(Cl. D49—1)

The parallel lines appearing on the front of the dryer in FIG. 3 are intended to represent shading within the interior thereof.

The dominant features of my design reside in the portions shown in full lines.

I claim:

The design for a portable clothes dryer, as shown and described.
